WAVE GENERATING SYSTEM

Maurice Artzt, Princeton, N. J., assignor to Radio Corporation of America, a corporation of Delaware

Application November 29, 1944, Serial No. 565,737

7 Claims. (Cl. 171—252)

1

The present invention relates to tone generators.

The operation of certain electrical systems requires an energy wave of constant frequency which is periodically keyed on and off at a relatively low rate. When the source of energy available is of a frequency lower than that required, a "chopped" energy wave of the above nature may be produced electronically by means of doubling circuits and keying tubes, but this introduces additional components which not only increase the complexity of the system but are subject to electrical or structural failure.

It has been proposed to generate such a periodically chopped wave electro-mechanically by means of a tone generator the tone wheel of which has a portion of its teeth removed. While this proposal is satisfactory insofar as simplification of the system is concerned, it introduces an undesirable feature in that not only is the required tooth frequency obtained in the output, but in addition there is present a component representative of the unwanted chopping frequency.

The present invention overcomes the disadvantage attendant upon the utilization of an electro-mechanical device for producing a chopped energy wave by providing a method and means for substantially reducing the amplitude of the unwanted chopping frequency component in the output thereof. Moreover, not only is the amplitude of the unwanted chopping frequency component substantially reduced by means of the present invention, but in addition the amplitude of the required tooth frequency is increased, thereby raising the ratio between the two to a point where the chopping frequency component may be disregarded for most practical applications.

The principal object of the present invention, therefore, is the provision of a method and means for producing electro-mechanically a chopped base wave having a high amplitude ratio of base frequency to chopping frequency.

A further object of the present invention is the provision of a method and means for producing, from a tone generator having a tone wheel with its teeth arranged in spaced-apart groups, an output in which the tone developed by the individual teeth on the wheel is relatively large in comparison with the tone developed by each group of teeth.

Other objects and advantages will be apparent from the following description of a preferred form of the invention and from the drawings, in which:

Fig. 1 is a partially schematic illustration of a

2

preferred form of apparatus embodying the present invention; and

Fig. 2 is a set of curves illustrating the operation of the apparatus of Fig. 1.

5 In Fig. 1 is shown a tone generator including a tone wheel 10 mounted for rotation on a shaft 12. Tone wheel 10 has on its periphery two similar groups of like teeth 14 and 16, the teeth in these groups being evenly spaced, and with each tooth in one group diametrically opposed to the corresponding tooth in the other group. In practice a tone wheel having such a configuration may be produced by removing from the periphery of a conventional tone wheel two diametrically-opposed sets of teeth, thus dividing the remaining teeth into two similar groups with equal spacing therebetween.

10 A pick-up device consisting of a magnet 18 having a coil 20 wound thereon is positioned adjacent the tone wheel 10 in the usual manner, so that upon rotation of wheel 10 the magnetic field surrounding magnet 18 will be cut by passage therethrough of the teeth comprising groups 14 and 16. This produces in coil 20 voltage changes represented by the composite waveform 22, curve (a) of Fig. 2, the wave portion illustrated being that produced by passage of either tooth group 14 or 16.

15 Composite wave 22 is made up of two component waves, one a substantially sinusoidal wave having the frequency and nominal amplitude of wave 22, and indicative of the frequency of passage of the individual teeth of either group 14 or 16 past the magnet 18, and the other a substantially sinusoidal wave 24 of lower frequency and lesser amplitude than wave 22, and indicative of the frequency of passage of that particular group of teeth past the magnet 18. From the above it will be apparent that wave 22 departs from a substantially sinusoidal state by an amount equal to the instantaneous amplitude of wave 24. It is this wave 24 which is an undesirable factor in the output of the tone generator, and which the present invention provides a method and means for reducing by a substantial degree in a manner to be described.

20 Referring again to Fig. 1, there is indicated by the reference character 26 a second magnet which is positioned similarly to magnet 18 in that its magnetic field is cut by passage therethrough of the teeth on the tone wheel 10. A coil 28 is wound on magnet 26.

25 Assuming that magnet 26 were diametrically opposed to magnet 18, or in other words if these two magnets were 180° apart with reference to

the shaft 12, then the output of coil 28 would be 180° out of phase with the output of coil 20. By connecting the coils in series, the wave 24 would be cancelled out. However, such a procedure would also cancel out the wave 22.

By shifting the magnet 26 from such an opposed position to a new position which is offset therefrom by an amount equal to $\theta/2$, where θ is the angle between the mid-points of adjacent teeth in either group, cancellation of wave 22 is avoided. This is illustrated by curves (b) and (c) of Fig. 2. In curve (b), the wave 30 produced in coil 28 and corresponding to the wave 22 of curve (a) is inverted with respect to wave 22 (denoting the assumed 180° out-of-phase relationship of the coils), and then shifted to the right an amount equal to $\theta/2$ (Fig. 1), or in other words by one half cycle of wave 30. This causes the in-phase peaks of waves 22 and 30, such as those indicated at 32 and 34 for example, to occur simultaneously, and the waves 22 and 30 accordingly add together so that the combined output of the coils 20 and 28 appearing across the output conductors 36 (Fig. 1) is of an increased amplitude as shown for example by the peak 38 of wave 40 in curve (c).

As shown in Fig. 2, the wave 42 of curve (b) representative of the frequency of passage of one group of teeth past magnet 26, and corresponding to wave 24 of curve (a), is shifted only slightly from its assumed 180° out-of-phase relationship with wave 24 due to its lower frequency with respect to wave 30. As a consequence, waves 24 and 42 still cancel one another to a considerable degree, and the resultant wave 44 of curve (c) will have a lower amplitude than either of waves 24 or 42 alone. Thus the energy waves 22 and 30, representing the tones respectively developed in the two coils 20 and 28 by the individual teeth on wheel 10, add together, while the waves 24 and 42, representing the tones respectively developed in the same two coils by the groups of teeth, oppose one another.

While two groups of like teeth have been shown, it will be clear that two additional groups of like teeth, or any number of groups in multiples of two, may be employed as long as each tooth in one group is diametrically opposed to the corresponding tooth in another group.

The two outer teeth in each group are preferably reduced from their original height shown by the broken lines in Fig. 1, thereby preventing sharp voltage changes in coils 20 and 28 when the groups enter or leave the vicinity of magnets 16 and 26, and maintaining the sinusoidal character of the wave output in a manner which will be readily understood by those skilled in the art.

I claim:

1. In a tone generator, a tone wheel having a plurality of diametrically-opposed teeth arranged in groups, a pair of magnetic pick-up devices positioned adjacent the periphery of said tone wheel and offset from a diametrically-opposed relationship thereto, means for connecting said pick-up devices in series in an output circuit, means responsive to the passage of the individual teeth on said wheel when the latter is rotated to produce voltage changes in the said pick-up devices which are in phase addition in the said output circuit, and means responsive to the passage of the said groups of teeth on said wheel to produce voltage changes in the said pick-up devices which are in phase opposition in the said output circuit.

2. The combination according to claim 1, in

which each of said pick-up devices comprises a magnet having a coil wound thereon, the said voltage changes being developed across said coils, and the said coils being series-connected in said output circuit.

3. In a tone generator, a tone wheel having a plurality of diametrically-opposed like teeth arranged in groups, the teeth in each group having equal spacing therebetween, and a pair of pick-up devices positioned adjacent the periphery of said tone wheel, said pick-up devices being offset from a diametrically opposed relationship relative to the axis of said wheel by an amount equal to half the angle between corresponding points on adjacent teeth of any of said groups.

4. The combination according to claim 3, further comprising means for connecting together said pick-up devices, and means responsive to the rotation of said tone wheel for producing in the combined output of said connected pick-up devices a component indicative of the frequency of passage of said groups of teeth past said pick-up devices that will be smaller in amplitude than the corresponding component in the output of each individual pick-up device.

5. In a tone generator: a tone wheel having two sets of equally-spaced diametrically-opposed like teeth, each set of teeth extending over substantially less than half the circumference of said wheel; a first magnet arranged so that upon rotation of said wheel said teeth will pass through the magnetic field surrounding said magnet; a coil wound on said first magnet; a second magnet also arranged so that its field will be cut by passage of said teeth, said magnets being so positioned that the largest of the angles formed thereby considered with respect to the axis of rotation of said wheel is

$$180^\circ + \theta/2$$

where θ is the angle measured in degrees between the mid-points of adjacent teeth in either set; a coil wound on said second magnet; means for connecting the two coils; and means responsive to the rotation of said tone wheel for producing in each coil electrical waves indicative of the frequency of passage of the individual teeth of said sets through the respective magnetic fields of said magnets which will be in phase addition, while the electrical waves produced in each coil indicative of the frequency of passage of said sets of teeth through the respective magnetic fields of said magnets will be substantially in phase opposition.

6. In an electrical generating system in which there is developed a composite wave consisting of two component waves, one of which is both of a lower frequency and a lesser amplitude than the other component wave, the method of reducing the relative amplitude of said one component wave in the output of said system which comprises the steps of generating a second composite wave substantially identical in form with said first-mentioned composite wave and differing from a phase-reversed relationship with respect thereto by an amount equal to approximately one-half the wave length of said other component wave, and combining said two composite waves.

7. In an electrical generating system in which there is developed a composite wave consisting of two component waves, one of which is of a lower frequency than the other component wave, the method of reducing the relative amplitude of said one component wave in the output of said

system which comprises the steps of generating a second composite wave substantially identical in form with said first-mentioned composite wave and differing from a phase-reversed relationship with respect thereto by an amount equal to approximately one-half the wave length of said other component wave, and combining said two composite waves.
